UNITED STATES PATENT OFFICE.

JOHN E. WRIGHT, OF NEW YORK, N. Y., ASSIGNOR TO AUSTEN H. FOX, OF NEW YORK, N. Y.

STREET-TRAFFIC-SIGNAL DEVICE.

Application filed July 12, 1922. Serial No. 574,493.

The invention subject of this application for Letters Patent is an improvement in street traffic signaling systems such as are now being adopted and use both in cities and elsewhere for the control and regulation of vehicles at the intersections of streets and roadways. In these systems, as heretofore employed, the control has been mainly, if not exclusively, manual, but my object has been to devise a system more nearly automatic in its operation and in which the indicating or warning signals may be controlled from more or less central points, not necessarily and purely automatically, but with provision for manual control when conditions arise which make such control desirable or necessary.

A primary object of the invention has been to provide for meeting such conditions of traffic as arise chiefly in the cities and larger towns in a simpler and less expensive manner than has heretofore been practiced, and at the same time to provide for exceptional conditions. For example, in the case of a fire or some catastrophe, should it become necessary to throw and set all signals to indicate danger and thus stop all traffic, this may be accomplished manually, without interfering with or impairing in any way the automatic control which at any moment may be resumed.

In carrying out the invention I have adopted for each signal post or station three sources of light. These may be gas jets or electric lamps, and may be operated by either gas or electricity conveyed from any suitable source through pipes or conductors. The description which follows will be confined to electric lighting systems, but at the present state of the art, those skilled in such matters will readily perceive, and, if required, will follow the steps that are necessary for the utilization of either one or the other.

In general terms, the system involves the use of either one or another of the three lamps employed with each signal post at any given time. For example, two of the lamps are enclosed in a revolving translucent screen of different colors, and the third in a compartment at the top of the post having display openings, the lamp either having a distinctive color, or the openings being provided with colored glass. This upper light is used in emergencies to stop all

traffic, during which the two lower lights are cut entirely out of circuit or action. Again the upper of the two lower lights is used only at night, while the lower one only by day. The signal post is provided with mechanism, controlled from a central station which determines the color or period during which the particular light is displayed, and this mechanism is operated by a novel arrangement of circuits and mechanisms which may be more readily comprehended from the detailed description which follows, and in which references are made to the accompanying drawings.

In these drawings—
Fig. 1 is a view in central vertical section of a lantern mechanism which is intended to surmount a post or the like set at a proper point, as for example, the intersection of two streets.

Fig. 2 is a view mainly in elevation of portions of the interior mechanism and the colored translucent shield or screen which surrounds the two main signal lights.

Fig. 3 is a top plan view of the said interior mechanism, the lantern proper being shown in horizontal section.

Figs. 4 and 5 are sectional views of the colored shields or screens, showing the arrangement of the colors, Fig. 4 showing the lower and Fig. 5 the upper half of the same.

Fig. 6 is a diagram illustrating the electric circuits or wiring by means of which the signal lights are operated and controlled; and,

Fig. 7 is a plan view of a form of cam used in connection with the circuits as a means of control.

The lantern of Fig. 1 is supposed to be carried at the top of any suitable form of post or standard 1, permanently or removably set at the intersection of two or more streets or roads. The casing for this lantern 2 may be cylindrical, or polygonal, of any proper material and character and mounted upon a base plate 3 mounted on the post 1. The lantern contains two stationary lamps 4 and 5, properly set upon or supported by a standard 6 in the center of the lantern case. Around this standard is a sleeve 7 carrying or formed with a bevel gear 8, upon which is mounted and secured a plate 9, supporting a cylindrical shield or screen of glass, or any other suitable translucent material 10.

having sections or different colors. In the side walls of the lantern are set eight lenses 11 which project the light from the lamps in four directions.

5 The screen or shield 10 is designed to be revolved by intermittent steps or movements and for this purpose I secure a casting 12 in the bottom of the lantern which carries a bevel gear wheel 13 meshing with the gear 8. To the spindle 14 of this gear 13 is fixed a ratchet wheel 15, which is engaged by a pawl 16 carried by a lever 17 concentrically mounted with reference to the ratchet wheel and operated by the core of a solenoid 18 to 15 which said lever is connected by means of a link 19.

Within the lantern are four symmetrically spaced segments or blocks 20 the inner faces of which are arc-shaped and closely approach the revolving shield 10 and which serve to divide the lantern chamber into four light passages which provide direct outlets for the light from the lamps through the colored sections of the said shield.

25 Assuming the signal lights, as I have, to be produced electrically, a single conductor 21 extends from a central control station A to one or in series to any desired number of signal posts 1 to the ground at B. As a 30 source of current I have shown a battery 22 grounded at its centre at 23 and with its terminals connected to two switch plates 24 and 25. Between these plates is a central contact plate 26 connected with the conductor 21 and a switch lever 27 adapted to sweep over the contact plates, is connected with a contact stop 28. A cam plate 29 which is revolved at a predetermined and relatively slow rate of speed by clockwork 35 or by a motor of some other character has projections 30 which operate a spring retracted circuit closer 31 connected with the line conductor 21 causing it at predetermined intervals to make contact with the 40 stop 28.

45 The line conductor 21 includes the coils of the solenoid 32 at each signal post and also the coils of a polarized circuit controlling magnet 33, the armature 34 of which vibrates between stops 35 and 36, and is connected by a wire 37 to one pole of any suitable supplemental source of electric energy. The stop 35 is connected through the lower lamp 4 with a circuit closer 38 operating in 50 connection with a contact stop 39, connected to the other pole of the supplemental source, and also through the heating coils 40, surrounding an expansible metal bar 52, to the said other pole of that source. The stop 36 55 is connected to the upper lamp 5 of the pair and also to the colored lamp 41, which is contained in a compartment at the top of the lantern having four display openings 42 therein. The other terminal of this top lamp 60 41 is connected to a terminal 43 of a switch

44, while the lamp 5 is connected in the same way as lamp 4, to the terminal 45 of the switch lever 44.

The colors of the screen and their circumferential divisions are largely arbitrary, but I prefer those indicated and described. That is to say, the lower half of shield 10 has two equal sections of green 46, facing each other and occupying together 2/8 of the circumference, and intermediate red sections 47 occupying the remainder or 6/8 of the entire circumference. On the other hand, the upper half of the shield shown in Fig. 5 has two opposite sections of green 48 each occupying 1/8 of the circumference, two opposite sections of red 50 each occupying 1/8 of the circumference and intermediate sections of yellow 49 occupying together the remaining 4/8 of the circumference of the shield. Under the conditions assumed, for day operation the switch lever 27 is turned to connect one pole of battery 22 by the contact, say, 25, with the stop 28, and the cam disk 29 permitted to rotate at a relatively slow speed in the direction of the arrow 51. Each projection 30 when it encounters the lever 31, closes the circuit from 25 through the conductor 21 and this operates the pawl 16 to move the ratchet the distance of, say, two teeth, and throws the polarized armature to a position in which it connects lower lamp 4 with the supply circuit. The lamp remains in this circuit until a second current is sent through the polarized relay. If the ratchet has 32 teeth, and four impulses pass through the solenoid, the result will be a movement of rotation of the colored shield or screen to the extent of one quarter of a complete revolution, and by spacing the teeth, the shield may be caused to expose any given color for any given length of time during any one revolution. Thus, green may be brought into view for one street, held for a moment and then changed to red, which persists in both directions until by the next two impulses green is shown at the side or 90° lenses and so on.

55 At night the switch lever 27 is thrown onto contact 24 with the result that the current is reversed, which causes the polarized magnet to connect the lamp 5 with the circuit and throws out the lamp 4. The solenoid being neutral is not affected by the direction of the current, but continues to revolve the shield 10 exposing, say, first a green then a red, and then a yellow light alternately up and down the intersecting streets.

60 If the switch lever be shifted onto the central contact 26, no current will be sent to the solenoids. If it be shifted so as to close contacts 24 or 25 and the center contact at the same time, the solenoids and the polarized magnets are continuously energized, and the functions of the cam cease altogether.

In case of emergency, as when a fire occurs, which makes it necessary to block all traffic, the switch lever 44 which is conveniently located on or in the vicinity of a post, 5 is turned from the stop 45 to the stop 43 by a traffic officer or other person with authority—at the time when the polarized armature is in contact with the stop 36. This carries the current from the supplemental 10 source through the lamp 41 which is maintained continuously in circuit, and cuts out of the circuit both lamps 4 and 5. The mechanism for revolving the colored shields 15 is not interfered with, but as the lamps 4 and 5 are not lighted they produce no visible effect.

It is or may be desirable that all of the lamps, instead of burning continuously, should flash, and for this purpose the circuit from the switch lever 44 is split, one path being through the bar 38 and stop 39 and the other through a high resistance path including a heating coil 40, surrounding an 20 expansible metal bar 52, which normally 25 holds the bar 38 out of contact with the stop 39. When current passes through coil 40 the bar 52 is expanded and closes this contact with the result that a path of low 30 resistance is offered for the current which 35 lights up the lamp. Thereupon the heating effect of coil 40 is destroyed with the result that the contact is broken, to be again closed a moment later. Any other and suitable form of vibrator may be used for this purpose, that shown being merely typical of such means.

As above stated, the character and the manner of use of the colors is not of the essence of the invention and may be varied 40 to meet local or other conditions. As I have designed the apparatus it is my intention to use the lower light and the colors red and green during the day to control traffic, and the upper light and the colors yellow, green 45 and red during the night.

The arrangement of the colors on the glass shield is such that in changing the right of way—that is to say, green, from one street to another running at right angles, the color 50 red is always displayed in four directions for a moment, with the object of holding up all vehicular traffic to permit pedestrians to cross. At night, when traffic is light, a similar arrangement causes the red to show 55 after the green momentarily, until the full change is completed. This result is reached by the disposition of the projections on the cam disk at the central station.

I have shown two forms of cams. That 60 in Fig. 7 has two sets of projections which allow for two changes of lights in one direction if the shield be properly constructed, and colored. That is to say, the portion of the cam indicated at 53 may be assigned to 65 the green, or right of way, color, on a com-

paratively trafficless street, while the part 54 might be allotted to an important avenue, the traffic of which demanded a longer period of right of way. As a matter of fact, the cam projections might be made movable 70 or adjustable, so that any conditions of traffic on contiguous thoroughfares may be met.

From the foregoing it will be seen that by the use of this system traffic-controlling lamps operated automatically, by means of 75 a single control wire, may be placed at various points remote from a central station, and be made to display lights for the guidance of traffic whether varying or of equal volume, on contiguous cross thoroughfares. 80 The control at the central station, under ordinary circumstances is automatic, pre-arranged to meet known conditions, even though these vary. However, in case of ex- 85 ceptional conditions or emergencies the control of the lights may be effected manually without impairment of the automatic operation when resumed. The system is therefore both elastic and effective.

In the practice of the invention it will be 90 understood by those skilled in the art that certain precautions commonly recognized in all such systems should be taken. Among these may be mentioned the synchronizing, by well known means, of all of the lanterns 95 and the use of means at the central station to show these conditions at all times. Again, it will be understood that while the devices herein set forth are adapted for use with thoroughfares which cross at right angles, by properly constructing the lanterns streets running at any other angles may be similarly protected. These and other matters being well understood in the art, require 100 no further or detailed description.

Having now described my invention what I claim as new and desire to secure by Letters Patent is:

1. In a system of highway traffic control, the combination with a plurality of signal lanterns placed at the intersections of streets and roadways each containing two sets of lamps, one for use by day and the other by night, means in each lantern for displaying the lights of such lamps in different colors, a solenoid for operating said means whereby the color of the light displayed is changed, a polarized electro-magnetic switch for connecting with a source of current either the day or the night lamps, a controlling circuit from a central station including all the solenoids and all the polarized magnets of said switches and means in said circuit for sending over it currents in either direction for operating the light controlling means.

2. In a system of highway traffic control, the combination with each of a plurality of signal lanterns placed at desired positions, of two lamps, translucent shields or screens having different color sections, one for each

- lamp, means for operating said shields for displaying different colors, and means for switching in one or the other of said lights according to the conditions of traffic.
5. 3. In a system of highway traffic control, the combination with each of a plurality of signal lanterns placed at desired positions, of two lamps in each lantern arranged one above the other, a revolving translucent shield or screen having different color sections around each of the lamps, means for revolving the shields electrically from a central station, and means for switching in one or the other of the said lamps according to the traffic conditions.
10. 4. In a system of highway traffic control, the combination with a signal lantern of three lamps one designed to display a single color, means for causing the other two to display different colors successively, means for switching into circuit either of the two lamps last mentioned, means for throwing both out of action and the first-named lamp into circuit, a control circuit to the lantern from a central station, and means at said station for controlling such circuit.
15. 5. In a system for highway traffic control, the combination with each of a plurality of signal lanterns placed at desired points of a plurality of lamps, means for causing some
- of said lamps to display different colors, and means for causing one of them to display the same color, a controlling circuit from a central station for operating said first mentioned means, a neutral electromagnet therein for operating said first mentioned means and a polarized magnet in said circuit for determining which of the said lamps shall be brought into action.
6. A highway traffic control system comprising, in combination, a signal lantern, two lamps in said signal lantern, a translucent revolving shield with differently colored sections surrounding each lamp, a pawl and ratchet mechanism for revolving said shield step-by-step, an electromagnet for operating said pawl and ratchet mechanism, a circuit from a central station including said electromagnet, means at the station for making and breaking said circuit at predetermined intervals, a second circuit adapted to include either one of said two lamps, and a polarized electromagnet in said first mentioned circuit whereby either one of said two lamps may be included in said second mentioned circuit.
40. 45. 50. 55. In testimony whereof I hereto affix my signature.

JOHN E. WRIGHT.
